UNITED STATES PATENT OFFICE.

ALBERT F. ROBBINS, OF WALTHAM, MASSACHUSETTS.

TOOL FOR REMOVING THE ROLLERS OF BALANCE-WHEEL STAFFS IN WATCH-MOVEMENTS.

979,562.

Specification of Letters Patent. Patented Dec. 27, 1910.

Application filed June 2, 1909. Serial No. 499,802.

To all whom it may concern:

Be it known that I, ALBERT F. ROBBINS, a citizen of the United States, residing at the city of Waltham, in the county of Middlesex and State of Massachusetts, have invented new and useful Improvements in Tools for Removing the Rollers of Balance-Wheel Staffs in Watch-Movements, of which the following is a specification.

10 This invention relates to tools for removing the roller, so called, of balance-wheel staffs in watch-movements.

The tool of this invention comprises, in substance, a rotatable head held on a suitable support, a plurality of holders each suitable to hold a balance-wheel staff with its balance-wheel and roller and present the same for the removal of the roller from the staff and severally mounted on said rotatable head and projected therefrom with their axes parallel with each other and with the axis of the head and at a corresponding distance from the axis of said head, and a sliding ejector-rod suitably mounted and arranged for movement along an axial line coincident with the axial line of one holder of said holders placed in proper position therefor, and all otherwise substantially as hereinafter described and pointed out in the claims.

In addition to the above the tool of this invention embraces, in its detail construction and arrangement, other features of importance and advantage, all as hereinafter fully appears.

In the accompanying drawings, forming part of this specification, is illustrated, on an enlarged scale, a tool embodying all the features of this invention.

40 Figure 1 is a plan view showing one holder with a balance-wheel and its staff and roller in it in position to be operated on to separate the staff from the roller, or in other words, as commonly spoken, to remove the roller from the staff. Fig. 2 is an elevation at one end. Fig. 3 is a central longitudinal vertical section, on dotted line 3—3, Fig. 2. Fig. 4 is a perspective view of a holder detached and Fig. 5 is a central longitudinal vertical section of the holder, Fig. 4. Fig. 6 is a vertical section, in detail, on dotted line 6—6, Fig. 3.

In the drawings, A is the supporting post or standard; B is the rotatable-head or disk; C, C are a series of the tubular-holders for

balance-wheel staffs and rollers; D is the sliding horizontal plunger-rod for ejecting a staff from its roller, that is, removing a roller from a staff; and E is the means for operating or sliding the plunger-rod or 60 ejector D.

The supporting standard A consists of a circular base-plate A² which is continued upwardly in a central post A³ screw-threaded, at its upper end-portion, and thereon having rigidly screwed a horizontally extending tubular and open-ended cylinder or barrel A⁴.

F is a horizontal cylindrical rod which is arranged to be free to be turned or rotated 70 in and to project from the opposite open ends of the barrel A⁴. This rod F, at one projecting end, has an axial screw-threaded stud-projection F² and on this stud is axially screwed the rotatable disk or head B, thus placing the head B in a vertical position with one side face B², the face the farther removed from the barrel A⁴, exposed, and the other side face against the adjacent open end of said barrel A⁴.

The projecting end F³ of the rod F and which is at the opposite end thereof to its projecting end F² has a rotatable sleeve E² and this sleeve has a peripheral horizontally and laterally projecting cam-rim E³ which 85 lies and works against the open end A⁵ of the barrel and is confined thereto, and so as to have suitable frictional bearing thereon, as the sleeve E² is rotated, by means of the headed-screw A⁶ which is screwed into 90 the end F³ of the rod F, and has its head counter sunk in the end of the sleeve E² and of the attached rotatable-disk or head B, as hereinbefore explained.

Each balance-wheel holder C consists of a 95 tubular-barrel which is open at one end C² and at the other end has a closed head C³ with a radial slot C⁴ open at the periphery and terminating at the axial portion of the head, and between this closed and slotted head C³ and the opposite and open end C² of the holder, the holder is cut away, as at C⁵, for a portion of its length and along its opposite sides and between them in line with the radial slot C⁴ before referred to, 100 see Figs. 4 and 5. C⁶ is a peripheral flange at the open end of the tubular barrel or holder C. The drawings show five of the 105 holders C, and they are severally of the construction described but they vary as to the 110

width of the radial slots C⁴, for the purpose of adapting them, and thereby one and the same tool for use to remove the rollers from balance-wheel staffs of varying sizes.

5 The several holders C are carried, in common, by the rotatable-head B which is suitably bored out, as at B³, to receive them, and have their several axes in separate horizontal parallel lines and in lines parallel to 10 and at corresponding distances from the horizontal axial line of the head B, the rod F and the barrel A⁴ in which said rod F turns. The holders C are, each by its smaller end, inserted at the rear side of said 15 head in a bore B³ thereof and each is seated, by its flange C⁶, on the shoulder B⁵ at the enlargement B⁴ of said bore, all so that each holder can be moved in and out of the head-bore B³ in which it is placed within a given 20 limit, and so that the several holders are secure against accidental escape from the head. Further the head B has inwardly projecting radial pins B⁶ properly spaced, and each of these pins engages a separate 25 longitudinal peripheral grooves C⁷ of the flange C⁶ of a holder C and so while a holder is free for in and out movement as just above stated, it is held against rotation in the head-bore B³ containing it, and is always 30 presented in the same position.

The plunger or ejector rod, for removing a staff-roller, is free to be moved lengthwise to and fro, within a given limit, along a horizontal tubular-way D² which extends 35 from end to end at the upper side of the barrel A⁴, and the axial lines of said rod and said way are coincident with each other and are each at a distance from the axial line of the barrel A⁴ and rotatable-head B corresponding to that of the several holders C 40 therefrom.

D² is a longitudinal slot at upper side of the barrel A⁴ and D⁴ is a radial-pin of the ejector-rod D entering into said slot and the 45 two coöperate together to hold said rod D against turning in the way D² and to guide it and limit its forward slide along said way. The forward end D⁵ of the sliding ejector-rod D is conical in shape, and it has 50 an axial socket D⁶ by which to enter the rod onto and thus engage it with the end of a balance-wheel staff H, as will hereinafter more fully appear. The diameter of the ejector-rod D is such that it can be entered 55 into and through the bore of a balance-wheel holder C, when one is in line therewith, and the length of said rod is such that it can have sufficient forward movement for its conical-end D⁵ engaged with a staff H as 60 stated, to secure the forcing of such staff out of its "roller" H² and so to remove the "roller" from the staff; the "roller", Fig. 1, at this time, being fixed in position and so held against movement by its resting 65 against the inside face of the end-wall or

head C³ of the holder C, with the hub H³ of the staff H lying within the radial slot C⁴ of said holder-head C³ and the balance-wheel H⁴ at the outer side thereof.

The rear end D⁷ of the ejector-rod D is 70 situated for the cam E³, as its carrying-sleeve E² is rotated, to work against, and thus secure the forcing of the rod forward as described, and the rod D, otherwise than has been above explained, is of such length 75 that with its forward end engaged with the rotatable-head B, holding it against turning, its opposite end can then extend into and be engaged with a socket E⁴ of the rotatable-cam-sleeve E² and so hold said sleeve and 80 its cam against turning, while, at the same time, the rod D can be properly positioned for its operation as has been explained.

It is evident from the foregoing description, that, with the rotatable-head B released 85 for movement, by disengaging the ejector-rod D therefrom, any one of the holders C can be placed and held in operative position for said rod to eject the staff of the balance-wheel carried by it from the "roller," or in 90 other words, to remove the "roller;" that the holder C positioned as above stated can be set out as shown, Fig. 1, from the other holders, by a simple outward drawing of it, which plainly is permissible, and thus the 95 balance-wheel carried by it is set off or away from the other holders; that the several balance-wheel holders, varying as has been stated, permit the same tool to be used for varying sizes of balance-wheels; that any 100 holder can be readily removed as may be desired for the substitution of another for it, or for any other reason; that the holders C act as receptacles to catch and retain or hold the removed "roller" as it drops from the 105 staff; that the rotatable-head B may have any number of holders C, and that the ejector-rod D may be operated directly by the hand in lieu of by the rotatable cam-head E² but it is preferable to operate it by a 110 cam-head such as E².

K is a coiled spring contained in the socket of the rotatable cam-head E², for automatically holding the ejector-rod F out of engagement with said cam-head. This spring 11 K, however, may be dispensed with.

Having thus described my invention what I claim and desire to secure by Letters Patent is,

1. A tool, for removing watch-rollers from 12 balance-wheel staffs, comprising a head, suitably supported, a tubular-holder for a balance-wheel, its staff and roller which are carried by and projected from said head, and adapted to present the axial line of the staff 1 along the axial line of the holder and to have the roller at rest flatwise against the outer end-wall thereof and a sliding ejector-rod, suitably supported, with its axis along 1 a line coincident with the axial line of said 1

holder and which is arranged and adapted to be entered into said holder, and to act on the projecting end of the staff which is toward it, in combination with a rotatable cam, suitably supported, and which is arranged and adapted to operate on said ejector-rod and thereby to slide it forward into said tubular-holder and therein to work on the projecting end of the staff which is toward it.

2. A tool, for removing watch-rollers from balance-wheel staffs, comprising a rotatable-head, suitably supported, and a plurality of tubular-holders for balance-wheels and their staffs and rollers, which are severally carried by and projected from said head, and are adapted to be moved outwardly and inwardly on the head, and have their several axes along parallel lines and at corresponding distances from and parallel with the

axis of said holder and each adapted to present the axis of the staff which it holds along its axial line and to have the roller at rest flatwise against the outer end-wall thereof, in combination with a sliding ejector-rod, 25 suitably supported, with its axis along a line at a corresponding distance from the axial line of said rotatable-head to that of said holders, and otherwise arranged and adapted to be entered into a holder of the said 30 plurality of holders, which is placed in line therewith, and therein to act on the projecting end of the staff which is toward it.

In witness whereof, I have hereunto set my hand in the presence of two subscribing 35 witnesses.

ALBERT F. ROBBINS.
